(57) **CLAIM**

The ornamental design for a photodynamic therapy lamp head, as shown and described.

DESCRIPTION

FIG. 1 is a perspective view of a photodynamic therapy lamp head, showing our new design, with the photodynamic therapy lamp head in a folded mode;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a perspective view of a photodynamic therapy lamp head, with the photodynamic therapy lamp head in an unfolded mode;

FIG. 8 is a front view thereof;

FIG. 9 is a rear view thereof;

FIG. 10 is a left side view thereof;

FIG. 11 is a right side view thereof; and,

FIG. 12 is a top view thereof.

The dashed lines in the drawings depict portions of the photodynamic therapy lamp head that form no part of the claimed design. The dot-dash broken lines depict the bounds of the claimed design and form no part thereof.
